(57) **CLAIM**

The ornamental design for an electrical enclosure, as shown and described.

DESCRIPTION

FIG. 1 is an upper right perspective view of the electrical enclosure;

FIG. 2 is a lower right perspective view of the electrical enclosure;

FIG. 3 is a rear perspective view of the electrical enclosure;

FIG. 4 is a front elevational view of the electrical enclosure;

FIG. 5 is a left side elevational view of the electrical enclosure;

FIG. 6 is a right side elevational view of the electrical enclosure;

FIG. 7 is a rear elevational view of the electrical enclosure;

FIG. 8 is a top plan view of the electrical enclosure; and,

FIG. 9 is a bottom plan view of the electrical enclosure. The long-dashed lines are for illustration of the boundary between claimed subject matter and unclaimed subject matter only and form no part of the claimed design. The short-dashed lines are for illustration of environmental subject matter only and form no part of the claimed design.

1 Claim, 7 Drawing Sheets
